PACKAGE HOLDER FOR DYEING MACHINES

Henry V. Underwood, Belmont, N. C.

Application November 5, 1931. Serial No. 573,130

3 Claims. (Cl. 8—19)

This invention relates to a package holder for dyeing machines and more especially to a package holder for receiving a bobbin, cop, or the like in a dyeing machine having a chamber thru which the dyestuff is forced and forced thru the inside of the bobbin, cop, or the like, and is forced outwardly thru the yarn on the perforated tube and then is withdrawn from the chamber in which the packages of yarn are mounted on the holders and again, forced thru the pipes and thru the yarn again and again or if desired the operation is reversed in many instances by forcing the dye thru the yarn on the package and into the interior of the holder and from thence into the pipe or hollow member to which the holder is secured.

Heretofore, means have been employed for holding a package of yarn which is usually wound on a perforated tube but in the conventional means such as an extended shaft and the like with a nut or other fastening means on the end thereof, the heated dye liquor expands the rod and therefore leakage occurs at the ends of the tube on which the yarn is wound, but by providing a spiral resilient member onto which the tubes with the yarn therein is slipped and secured in place by means of a nut on the end thereof, the spiral direction given to the flow of the liquid causes the tube to be turned in the same direction as the nut on the end thereof so as to cause the nut to automatically follow the tube and to become farther advanced on the holder to prevent any leaking whatever occurring between the tube holding the yarn and the nut at the end thereof or the base member against which the tube fits.

It is an object of this invention, therefore, to provide a holder for packaged yarn which is wound onto perforated or porous tubes whereby the ends of the tubes will be sealed at all times and the direction of the dye liquor within the tube will cause the tube to automatically turn the nut with it, due to the force of the dye liquor passing along the spiral within the tube to prevent any leakage of the dyestuff at the ends of the tube but will cause the dyestuff to be forced out thru the perforations in the tube and the yarn on the tube.

The spring-like structure allows sidewise and up and down movement of the free ends of the bobbin holders to move when they strike against the kier in being installed in and also in being removed from the kier. Also the structure allows distension of the holder when the nut on the

end is driven home and thus expansion is compensated for.

Some of the objects of the invention having been stated other objects will appear as the description proceeds when taken in connection with the accompanying drawing, in which—

Figure 1 is a view partly in elevation and partly in section showing my improved bobbin holder;

Figure 2 is a view with parts thereof in longitudinal section showing the structure of the spiral member for holding the tube and the yarn thereon;

Figure 3 is a cross sectional view taken along the line 3—3 in Figure 1.

Referring more specifically to the drawing, the numeral 10 indicates a hollow member such as a pipe into which the base 11 of the bobbin holder is adapted to be threadably secured by means of the threads 12 on the base fitting into threaded holes in the pipe member 10. This base member 11 is hollow and has fixedly secured therein a spiral resilient member 13 which has fixed in the end thereof a member 14 which is threaded as at 15 and is adapted to receive a nut 16 for securing the tube 17, having perforations 18 thereon onto the holder and this tube is adapted to have wound thereon the yarn 19. The base member has a circular groove 20 therein into which the other end of the tube is adapted to fit.

The spiral member 13 is formed as to provide a passageway 21 as shown in Figure 3 all the way thru the spiral and also the spiral forms a circular passageway for the fluid so as to cause it to move in a spiral direction as it progresses thru the tube and this causes the tube to rotate in the same direction as the nut 16 is adapted to rotate so as to keep the nut tightened as the dye fluid passes thru the device so as to prevent leakage of the dyestuff at the ends of the tubes, but to cause the dyestuff to be forced out thru the tube.

Heretofore, in the conventional type of holder, there is a rod such as 14 extending all the way thru the tube and secured in the base member 10 by any suitable means, and when the dye liquor is turned into the device, the rod would expand and therefore allow leakage at the end of the tube, but due to the peculiar structure of this device, this is prevented because the spiral motion of the fluid causes the tube and nut 16 to turn at the same time and therefore prevent any leakage at either end of the tube 17.

Also due to the resiliency of the spiral member 13, it is possible to advance the nut 17 until the tube is held under tension at both ends thereof so that any expansion of member 13 due to

the heated dye liquor will fail to cause any leakage at the end thereof, and just before the expansion has been to a point so as to allow leakage, the circular motion of the dye liquor in the spiral will cause the nut and tube to turn together to prevent any leakage at the end of the tube.

In the drawing and specification there has been set forth a preferred embodiment of the invention and although specific terms are employed, they are used in a generic and descriptive sense only and not for purposes of limitation, the scope of the invention being set forth in the appended claims.

15 I claim:

1. In a package holder for yarn dyeing machines, a threaded hollow base member adapted to be secured in a supply pipe of the dyeing machine, a resilient spiral member secured in the base member and extending unsupported therefrom, a threaded member secured in the other end of the spiral member, a nut on said threaded member for resiliently confining the package of yarn between the base member and the nut.

25 2. In a package holder for a yarn dyeing ma-

chine, said machine having a supply pipe, a base member adapted to threadably engage a perforation in said supply pipe, a resilient spiral member having one end secured in said base member, said base member and spiral member having a passageway therein, a threaded member secured in the other end of said spiral member to close the passageway, a nut mounted on the threaded member for confining a package around the spiral member and against the base member.

3. A holder for dyeing machines for dyeing packages of yarn wound on a perforated tube, said holder comprising a base adapted to be secured in a dye supply pipe in the machine, a self-supported resilient spiral member secured in said base and extending therefrom far enough to extend beyond a perforated tube mounted therearound, a nut on the other end of said spiral member for confining the tube between the base member and the nut.

his
HENRY X V. UNDERWOOD.
